UNITED STATES PATENT OFFICE.

ALEXANDER MEISSNER, OF BERLIN, GERMANY, ASSIGNOR TO GESELLSCHAFT FÜR DRAHTLOSE TELEGRAPHIE M. B. H., OF BERLIN, GERMANY, A CORPORATION OF GERMANY.

RECEIVING ARRANGEMENT FOR WIRELESS TELEGRAPHY.

Application filed September 3, 1921, Serial No. 498,417, and in Germany March 6, 1917.

(GRANTED UNDER THE PROVISIONS OF THE ACT OF MARCH 3, 1921, 41 STAT. L., 1818.)

The present invention relates to a receiving arrangement for wireless telegraphy and telephony in which, a divided receiving system is used for the purpose of eliminating disturbances. For this purpose, previously known arrangements, so far as applicant is aware, have made use either of a plurality of antennæ or a single antenna having a plurality of branches. In the use of such known arrangements, one antenna or an antenna branch is tuned to the wave which it is desired to receive, whereas, the other antenna or other branch has a different individual oscillating period, and a detector circuit is usually placed in compensating connection with the parts of the receiving system, the disturbing energies transmitted from both parts of the receiving system being made equal so far as possible, and of opposite phase and the signalling energies being unequal, so that the detector is actuated only by the signalling energy.

Such arrangements give satisfactory results when it is desired to eliminate disturbances by a foreign wave, because in this case the disturbing energies have the same periodicity and approximately equal energy in both parts of the receiving system. However, the elimination of atmospheric disturbances is only partially accomplished by the arrangements. Two entirely separate antennæ are not energized with the same strength in response to all atmospheric disturbances, because of differences in the direction, capacity, responsiveness, etc. Moreover, in the case of an atmospheric impulse, different branches of an antenna receive most waves at different strengths and for this reason complete compensation cannot be effected. Finally, high frequency compensation such as is attempted to be effected in known arrangements can not give satisfactory results, because the disturbing energy is transmitted to the detector circuit in waves of different lengths, it being understood that high frequency compensation of two waves is possible only when the waves have the same amplitude and are of equal wave lengths and opposite phase.

In accordance with the present invention, these drawbacks are eliminated by an arrangement including a single antenna tuned

to two wave lengths, one of which is the wave length of the energy which it is desired to receive. Instead of attempting immediately to compensate the disturbing waves, energy received in the arrangement is transmitted to secondary circuits each of which is tuned to one of the above-mentioned wave lengths. The secondary circuits are loosely coupled with the antenna. In this manner, the energy received from space is entirely separated in the secondary circuits, one of them receiving only disturbing energy and the other both signalling and disturbing energy. Due to such separation of the energy, the disturbing energy can be completely compensated, since the respective portions of said energy in the secondary circuits may be easily equalized. In order to effect the compensation, according to the present invention, the portions of the disturbing energy in the secondary circuits are rectified by means of separate detectors and are transmitted into a low frequency circuit containing a common indicating apparatus. Thus, compensation is effected at low frequency and independently of different wave lengths of the high frequency energy. Finally, in accordance with the invention, detectors of substantially identical characteristics are used so as to cause equal disturbing energies to be transmitted by the detectors to the low frequency circuit. In previously known arrangements this has not been sufficiently taken into account. Entirely satisfactory results can be attained if a so-called audion is used as a detector.

The drawing represents in Figs. 1 and 2 circuit arrangements of different forms embodying the invention.

Fig. 1 shows a circuit arrangement for receiving modulated waves from tone senders. The antenna 1 is tuned to two wave lengths by means of a circuit 2 permanently coupled therewith, one of said wave lengths being that of the signals to be received. The antenna transmits signalling energy and disturbances to a secondary circuit 3 also tuned to the signals. Disturbances are also transmitted by the antenna to a separate secondary circuit 4 tuned to the other wave length to which the antenna is resonant. The secondary circuits 3 and 4 comprise de-

tectors 5 and 6, respectively. The portions of the disturbing energy in the respective circuits 3 and 4 are conducted from the block condensers 7 and 8 in the respective 5 circuits 3 and 4 in series opposition into a circuit including a telephone 9. As long as the antenna receives only atmospheric disturbances, the disturbances are completely eliminated, assuming that the detectors are 10 connected in series opposition and possess identical characteristics for all occurring different intensities. If, however, signals are added to the disturbances, the signalling energy will be transmitted mainly to the circuit 3 and will, therefore, not be compensated. In addition to the signal, slight disturbances will be heard in the telephone 9, because the detectors 5 and 6 will be caused 15 to operate at different points of their characteristics. This is not objectionable at such time but rather is an advantage because it increases the audibility of the signal. However, during the intervals between signaling, complete freedom from disturbances may be 20 attained in the use of the invention.

The invention can be used to even greater advantage for the receiving of undamped oscillations. A circuit arrangement for this purpose is illustrated in Fig. 2. The separation of the energies is accomplished e. g. 30 by intermediate circuits 3^a and 4^a between the two-wave antenna 1 and the detector circuits 3 and 4. The circuits 3^a and 4^a may be tuned correspondingly to the detector circuits 3 and 4, that is, to the wave length 35 of the signals to be received and to the other wave length to which the antenna is tuned respectively. Both detector energies are conducted in opposition through the retardation 40 coils 10 and 11 to the common collecting condenser 12, and from there, in the case of telegraphy signals, through a normally operating tone producing interrupter 13 to the telephone 9. The purpose of the retardation coils 10 and 11 or similar suitable 45 alternating current impedances is to prevent a mutual disturbance in the separate secondary high frequency circuits through the collecting condenser 12. There is again complete 50 compensation of the disturbances occurring between signals, but during signaling, there is now also an effect of the unneutralized disturbing energy which has also imparted to it a tone characteristic on the 55 telephone or other indicator 9.

It will be understood from the foregoing that in this compensating circuit arrangement, the intensity of the signals must be increased, for example, by the use of amplifying arrangements.

Preferably, the latter are employed in the detector circuit so as to improve the useful

effect of the connection which is somewhat lessened due to the compensation of the disturbances.

Claims.

1. In combination, a plurality of detectors, means for impressing desired and undesired electrical energies on said detectors, an indicator, means for affecting said indicator by the energies rectified by said detectors in opposite sense, and means whereby said detectors operate on the same portions of their characteristics when only undesired energy is impressed thereon and said detectors 75 operate on different portions of their characteristics when both undesired and desired energies are impressed thereon.

2. In combination, a plurality of detectors, means for impressing a signal frequency on 80 one of said detectors and undesired electrical energy on said plurality of detectors, an indicator, means whereby the rectified energies from said detectors affect said indicator in opposite sense, means whereby said undesired energy is neutralized during a 85 signalling interval but increases the effect of the signal frequency during a signalling period.

3. In combination, an indicating device, 90 parallel paths arranged to affect said device, means for impressing desired and undesired electrical energies on said paths, and means whereby the effect of said undesired energy on said device is nil when no desired energy 95 is impressed on said paths and said undesired energy augments the effect of the desired energy on said device when desired energy is impressed on said paths.

4. In combination, a plurality of circuits 100 each tuned to a different frequency, means for impressing desired and undesired frequencies on said circuits, a separate detector associated with each of said circuits, a condenser, means for impressing the frequencies 105 rectified by said detectors on said condenser in opposite sense, said means including impedances, and indicator means connected across said condenser.

5. A receiving arrangement for wireless 110 telegraphy and telephony comprising an antenna tuned to two wave lengths, one of which is the wave length of signalling energy to be received, secondary circuits loosely coupled with the antenna and tuned respectively to said wave lengths, detectors in the secondary circuits, a condenser with which the detectors are connected in series opposition, impedances interposed between the detectors and said condenser, a circuit including said condenser and an indicator in the last-mentioned circuit.

In testimony whereof I affix the signature.
ALEXANDER MEISSNER.
